UNITED STATES PATENT OFFICE.

WILLIAM M. LEE, OF OGDEN, UTAH, ASSIGNOR OF ONE-HALF TO LOUIS H. PEERY, OF OGDEN, UTAH.

DESIGN FOR A ROPE-CLAMP.

49,312.

Specification for Design.

Patented July 4, 1916.

Application filed October 30, 1915. Serial No. 58,923. Term of patent 14 years.

To all whom it may concern:

Be it known that I, WILLIAM M. LEE, a citizen of the United States, residing at Ogden, in the county of Weber and State of Utah, have invented a new, original, and ornamental Design for a Rope-Clamp, of which the following is a specification, reference being had to the accompanying drawing, forming a part thereof.

The figure is a side elevation of a rope clamp, showing my new design.

I claim:

The ornamental design for a rope clamp, as shown.

WILLIAM M. LEE.

Witnesses:

L. H. PEERY,
L. H. CARVER.
